UNITED STATES PATENT OFFICE

EDWARD W. STEVENS, OF DETROIT, MICHIGAN, ASSIGNOR TO CHICAGO PNEUMATIC TOOL COMPANY, OF NEW YORK, N. Y., A CORPORATION OF NEW JERSEY

PLATE VALVE MECHANISM FOR FLUID PRESSURE TOOLS

Application filed December 7, 1929. Serial No. 412,334.

This invention relates to fluid actuated percussive tools and particularly hand held machines in which the piston reciprocates in the cylinder and is controlled by a fluid actuated distributing valve. In the present embodiment of the invention the piston is of the free moving hammer type and is adapted to strike a working tool, but by providing a shank or piston rod to the piston it may be employed as a sand rammer or tamping tool and the like.

The objects of the invention are to improve the construction and operation of the automatic distributing valve which in this instance controls only the inlet of live pressure fluid to the cylinder. A free exhaust in the side of the cylinder is controlled only by the piston and the valve itself is an improvement on the so-called flap valve in which the flow or current of pressure fluid in conjunction with the drop of pressure beneath one end of the valve exerted against the other end of the valve causes the valve to operate. In accordance with this improved construction the valve is located rearwardly of the cylinder on a simple head block which is held in position by the handle or backhead.

The invention is illustrated in one of its preferred forms in the accompanying drawings in which:

Fig. 1 is a longitudinal sectional elevation of a chipping hammer;

Fig. 2 is a similar view with the piston and valve in a different position; and

Fig. 3 is a vertical fragmentary sectional view substantially on the line 3-3 of Fig. 2.

Referring to the drawings the backhead or handle A has the usual throttle mechanism and a live pressure fluid passage B leading to the valve chamber, and is secured to the cylinder C by threaded engagement or any other suitable method and within the backhead member A and rearwardly of the cylinder C is located the valve D and head block E upon which the washer shaped plate valve D works. As a means of keeping the valve centrally located on the head block E a tubular shaped member or band F is placed around the extended portion of the head block E that has the tapered valve seat, and as a means of

holding the valve down a retainer in the form of a small rod or shaft G is placed directly across and in line with the center axis of the valve seat and as a means of locating and holding the said retainer rod in proper relation to the valve seat recesses or grooves are cut on opposite sides of the band F to receive the ends of the rod. A key or dowel W keeps member F in proper relation with the head block E.

The valve D is a thin circular disk of uniform thickness and diameter and has a hole in the center through which the live motive fluid passes. The valve disk oscillates on the axis of the head block E and is kept centrally located by the surrounding member F. Only sufficient clearance is provided between the periphery of the valve and the bore of member F to prevent binding and permit free oscillation.

The head block E is provided with inlet ports H and V controlled only by the valve D. The inlet port H leads to the rear end of the cylinder while the inlet port V communicates with the passage J leading to the inlet port K at the forward end of the cylinder. Exhaust passages L in the cylinder communicate with the atmospheric exhaust ports M and with the exhaust ports N and N' located approximately as shown.

In the operation of the device let it be assumed that the piston O is at the forward end of the cylinder C and is in contact with the working tool P as indicated in Fig. 1 with the valve D also in the position indicated so that the live pressure fluid entering at the inlet B is exerting an equal pressure over the entire rear or top area of the valve D. The inlet port H being open to atmospheric pressure through the cylinder and exhaust ports N and M, the live air pressure on the opposite face of the valve causes it to tip down and close the said port H. Live air passes through the center opening in the valve and under it to the inlet port V thence through the duct J and port K into the forward piston chamber to drive the piston rearwardly. As piston O on its rearward movement uncovers the forward exhaust ports N', a drop of pressure results beneath the valve

at the inlet port V side and at the same time pressure in the inlet port H is built up by the piston closing the exhaust ports N and compressing the trapped air in the rear piston chamber. In consequence valve D moves to the position shown in Fig. 2 to admit motive fluid through port H to reverse the movement of the piston and drive it forwardly on its working stroke. When the piston 10 passes beyond the ports N on the forward stroke the pressure will drop at the rear and will build up at the forward end with sufficient pressure to tip the valve, and in that manner the cycle will repeat as the piston reciprocates.

The diameter of the hole in the valve D has an important relation to the angle of the valve seat and the area of the ports H and V. The reason for this is to permit the live 20 air to flow from the inlet ports H and V with slightly more freedom than through the clearance space between the rim of the valve bore and the seat, thus permitting the incoming air to follow or in other words to produce 25 a wire drawing effect with a drop in pressure beneath the valve, as previously described.

One of the important advantages of the present invention over known types of flat 30 valves is that it will permit the use of one valve of standard shape and size for all tools. The valve is exceptionally easy and inexpensive to make since it is a simple disk of uniform thickness. This valve is fool proof in 35 the sense that it does not require locating by dowels and can be inserted either side up. Being a flat disk it slowly rotates when in operation and thus wears uniformly.

While the invention has been herein disclosed in what is now considered to be a preferred form it is to be understood that it is not limited to the exact details thereof but covers all changes, modifications, and adaptations within the scope of the appended claims.

45 I claim as my invention:

1. In a fluid pressure tool having a reciprocating piston, valve mechanism for controlling the movements of the piston comprising a valve block having a valve recess 50 and providing a seat tapered in opposite directions, said block having ports extending through said tapered seat portions, and a plate valve in said recess for controlling said ports, said valve having an unrestricted bore therethrough for passing motive fluid to said ports in alternation.

2. In a fluid pressure tool having a reciprocating piston, valve mechanism for controlling the movements of the piston comprising a valve block having a valve recess 60 and providing a seat tapered in opposite directions, said block having ports extending through said tapered seat portions, a plate valve in said recess for controlling said ports, 65 said valve having an open bore therethrough

for passing motive fluid to said ports in alternation, and retainer means extending transversely of said block for maintaining said valve in said recess.

3. In a fluid pressure tool having a reciprocating piston, valve mechanism for controlling the movements of the piston comprising a valve block having a valve recess and providing a seat tapered in opposite directions, said block having ports extending through said tapered seat portions, a plate valve in said recess for controlling said ports, 70 said valve having a bore therethrough for passing motive fluid to said ports in alternation, and a central open retainer member extending across said block in line with the median of said tapered seat for maintaining said valve in said recess.

4. In a fluid pressure tool having a reciprocating piston, valve mechanism for controlling the movements of the piston comprising a valve block having a valve recess and providing a seat tapered in opposite directions, said block having ports extending through said tapered seat portions, a plate valve in said recess for controlling said ports, 75 said valve having a bore therethrough for passing motive fluid to said ports in alternation, and a central open retainer member extending across said block in line with the median of said tapered seat for maintaining said valve in said recess.

5. In a fluid pressure percussive tool having a cylinder with a piston reciprocable therein and a head with a motive fluid inlet secured to said cylinder, a valve block interposed between said cylinder and head comprising a seat member forming a closure for the end of the cylinder and providing semi-circular seats tapered from a median line, 80 said member having ports extending through said seats for directing motive fluid to opposite ends of said cylinder, and a plate valve in the form of a washer having a central aperture mounted to oscillate on said median line to control said ports, the aperture in said valve being unrestricted for the passage of motive fluid to said ports.

6. In a fluid pressure percussive tool having a cylinder with a piston reciprocable therein and a head with a motive fluid inlet secured to said cylinder, a valve block interposed between said cylinder and head comprising a seat member forming a closure for the end of the cylinder and providing semi-circular seats tapered from a median line, 85 said member having ports extending through said seats for directing motive fluid to opposite ends of said cylinder, an annular member inclosing said seats to define the valve chamber, and an annular plate valve within said chamber loosely fitting said last named member for oscillating movement on said median line to control said ports, the aper- 90

ture in said valve serving to pass motive fluid to said ports.

7. In a fluid pressure percussive tool having a cylinder with a piston reciprocable therein and a head with a motive fluid inlet secured to said cylinder, a valve block interposed between said cylinder and head comprising a seat member forming a closure for the end of the cylinder and providing semi-circular seats tapered from a median line, said member having ports extending through said seats for directing motive fluid to opposite ends of said cylinder, an annular member in keyed and telescoping engagement 5 with said seat member to define the valve chamber, and an annular plate valve within said chamber loosely fitting said last named member for oscillating movement on said median line to control said ports, the aperture 10 in said valve serving to pass motive fluid to said ports.
10. In a fluid pressure percussive tool having a cylinder with a piston reciprocable therein and a head with a motive fluid inlet secured to said cylinder, a valve block interposed between said cylinder and head comprising a seat member forming a closure for the end of the cylinder and providing semi-circular seats tapered from a median line, 15 said member having ports extending through said seats for directing motive fluid to opposite ends of said cylinder, an annular member in keyed and telescoping engagement 20 with said seat member to define the valve chamber, and an annular plate valve within said chamber loosely fitting said last named member for oscillating movement on said median line to control said ports, the aperture 25 in said valve serving to pass motive fluid to said ports.

8. In a fluid pressure percussive tool having a cylinder with a piston reciprocable therein and a head with a motive fluid inlet secured to said cylinder, a valve block interposed between said cylinder and head comprising a seat member forming a closure for the end of the cylinder and providing semi-circular seats tapered from a median line, 25 said member having ports extending through said seats for directing motive fluid to opposite ends of said cylinder, a plate valve in the form of a washer mounted to oscillate on said median line to control said ports, said 30 valve having an aperture in line with said inlet for passing motive fluid to said ports, and means in parallelism with said median line for retaining said valve in place.

9. In a fluid pressure percussive tool having a cylinder with a piston reciprocable therein and a head with a motive fluid inlet secured to said cylinder, a valve block interposed between said cylinder and head comprising a seat member forming a closure for 45 the end of the cylinder and providing semi-circular seats tapered from a median line, said member having ports extending through said seats for directing motive fluid to opposite ends of said cylinder, an annular member in keyed and telescoping engagement with said seat member to define the valve chamber, an annular plate valve within said chamber loosely fitting said last named member for oscillating movement on said median line to 50 control said ports, the aperture in said valve serving to pass motive fluid to said ports, and means on said annular member for retaining said valve in operative position in said valve chamber.

10. In a fluid pressure percussive tool having a cylinder with a piston reciprocable therein and a head with a motive fluid inlet secured to said cylinder, a valve block interposed between said cylinder and head comprising a seat member forming a closure for

the end of the cylinder and providing semi-circular seats tapered from a median line, said member having ports extending through said seats for directing motive fluid to opposite ends of said cylinder, an annular member 70 in keyed and telescoping engagement with said seat member to define the valve chamber, an annular plate valve within said chamber loosely fitting said last named member for oscillating movement on said median line to 75 control said ports, the aperture in said valve serving to pass motive fluid to said ports, and means on said annular member for retaining said valve in operative position in said valve chamber comprising a rod disposed in parallelism with said median line.

11. A fluid pressure percussive tool having a cylinder provided with one exhaust port communicating with atmosphere, a piston reciprocable in said cylinder and controlling 85 said exhaust port, a head having a conduit for motive fluid secured to said head, a valve block forming a closure for said cylinder and clamped against the latter by said head, said block having a circular valve recess and providing valve seats therein tapered from a median line, said block having ports in said seats communicating with the opposite ends of said cylinder, an annular valve in said chamber 90 for oscillatory movement on said line to control said ports, the aperture in the valve being free of restriction and of a size bearing a critical relation to the taper of said seats whereby when one of said seat ports uncovered by said valve is put in communication 95 with atmosphere by said piston a drop in pressure under said valve will result tending to cause said valve to close said port.

12. A valve assembly for fluid pressure tools comprising a valve block providing a 105 circular valve recess having valve seats tapered in opposite directions from a median line, said block having ports in said seats, and an annular flat disk valve of uniform thickness loosely fitting said recess for oscillatory movement on said median line to engage said seats and to control said ports in alternation, said valve being free to rotate in said recess.

13. In a valve assembly for fluid pressure 115 tools, a block comprising a seat member and another member in interengaged relation to provide a valve recess, said seat member providing seats tapered oppositely from a median line and ports in said seats, a plate 120 valve in said recess for controlling said ports, and a retainer member on said other member extending across said recess in parallelism with said median line, said retainer member loosely engaging the exterior of said valve 125 to leave the latter free for rotary movement in said recess.

14. In a valve assembly for fluid pressure 130 tools, a block comprising a seat member and an annular member in interfitting keyed re-

lation to provide a circular valve recess, said seat member providing seats tapered oppositely from a median line and ports in said seats, a plate valve in the form of a washer
5 loosely fitting said annular member to permit oscillatory movement in said recess on said median line, said annular member having aligned recesses remote from said seat member, and a retainer member seated in said
10 aligned recesses and spanning said valve recess in substantial parallelism with said median line, said retainer member loosely engaging the face of said valve remote from said seats.

CERTIFICATE OF CORRECTION.

Patent No. 1,837,799.

Granted December 22, 1931, to

EDWARD W. STEVENS.

It is hereby certified that error appears in the printed specification of the above numbered patent requiring correction as follows: Page 2, line 80, claim 3, strike out the words "central open" and insert same to follow the article "a" in line 78, of same claim; and that the said Letters Patent should be read with this correction therein that the same may conform to the record of the case in the Patent Office.

Signed and sealed this 9th day of February, A. D. 1932.

(Seal)

M. J. Moore,
Acting Commissioner of Patents.
